US00D541419S

(12) **United States Design Patent** (10) **Patent No.:** **US D541,419 S**
(45) **Date of Patent:** **** Apr. 24, 2007**

(54) **HAND-HELD SPIROMETRY DEVICE**

(75) Inventor: **William C. Jones, Jr.**, Chicago, IL (US)

(73) Assignee: **Jones Medical Instrument Company**, Oak Brook, IL (US)

(**) Term: **14 Years**

(21) Appl. No.: **29/223,514**

(22) Filed: **Feb. 15, 2005**

(51) **LOC (8) Cl.** **24-01**

(52) **U.S. Cl.** **D24/164**

(58) **Field of Classification Search** D24/112-114, D24/186, 164; D19/45, 51; 600/533, 537, 600/538; 128/204.12, 204.18, 204.21, 204.22, 128/204.23

See application file for complete search history.

(57) **CLAIM**

The ornamental design for a hand-held spirometry device, as shown and described.

DESCRIPTION

FIG. 1 is a perspective view showing my new design; FIG. 2 is a front view of the hand-held spirometry device of FIG. 1;

FIG. 3 is a bottom view of the hand-held spirometry device of FIG. 1;

FIG. 4 is a rear view of the hand-held spirometry device of FIG. 1;

FIG. 5 is a top view of the hand-held spirometry device of FIG. 1;

FIG. 6 is a right side view of the hand-held spirometry device of FIG. 1;

FIG. 7 is a left side view of the hand-held spirometry device of FIG. 1;

FIG. 8 is a perspective view showing a second embodiment of my new design;

FIG. 9 is a front view of the hand-held spirometry device of FIG. 8;

FIG. 10 is a bottom view of the hand-held spirometry device of FIG. 8;

FIG. 11 is a rear view of the hand-held spirometry device of FIG. 8;

FIG. 12 is a top view of the hand-held spirometry device of FIG. 8;

FIG. 13 is a right side view of the hand-held spirometry device of FIG. 8; and,

FIG. 14 is a left side view of the hand-held spirometry device of FIG. 8.

The dashed lines are for illustrative purposes only and form no part of the claimed design.

1 Claim, 4 Drawing Sheets
